DEPARTMENT STORE MACHINE

Frederick L. Fuller and George F. Daly, West Orange, N. J., assignors to International Business Machines Corporation, New York, N. Y., a corporation of New York

Original application December 4, 1935, Serial No. 52,766. Divided and this application October 23, 1936, Serial No. 107,142

2 Claims. (Cl. 235—60)

This case relates to recording machines and is a division of application Serial No. 52,766, filed December 4, 1935.

In particular, the invention deals with a machine for recording sales transactions in large stores such as department stores. The sales transaction is recorded by the machine on a sales slip or the like in the form of a printed record, and is also recorded on a tabulating card in the form of a punched coded record. The printed sales slip is usually given to the customer, while the punched card is retained in the store and subsequently used to control tabulating machines for tabulating the information on the card.

Broadly, the invention in this divisional case relates to the keyboard of a novel, improved, machine for recording data pertaining to the article sold, to the clerk making the sale, and to the customer.

The main object is to provide a new key-controlled mechanism to enter an item in an item-entry receiving means or in differentially operable means, such as item indicating elements, type members, punching members, or the like value or item manifesting means.

Other objects are to provide novel card ejecting means and novel positioning means for the sales slip.

Still other objects will appear in the following parts of the specification and from the drawings, in which:

Fig. 1 is a plan section through the machine; Figs. 2 to 6 are respectively sections along lines 2 to 6 of Fig. 1;

Fig. 6a is a detail of an item wheel on a punch slide with the item wheel in section;

Fig. 7 is a section along lines 1—7 of Fig. 1; Fig. 8 is a section along lines 8—8 of Fig. 3;

Fig. 9 is a section along lines 9—9 of Fig. 1; Fig. 10 is a section along lines 10—10 of Fig. 1; Fig. 11 is a section along lines 11—11 of Fig. 2; Fig. 12 is a section along lines 12—12 of Fig. 2; Fig. 13 is a detail section taken along lines 13—13 of Fig. 1.

The present invention is directed to the setting of nine punch slides; i. e., the amount, transaction, and clerk number punch slides 10a, t, and c and the setting of the corresponding type wheels 43a, t, and c under control of a ten key keyboard; as will now be explained.

Ten key control

There are ten keys 15, one for each of digits 0 to 9, as shown in Figs. 1 and 2. These keys are mounted for vertical movement in the frame (see Fig. 4) and their stems are bent transversely, as shown in Fig. 2 to place their lower portions in parallel planes, side by side.

The disposition of the various key stems is in-

dicated at the bottom of Fig. 2 by the digital values to which the stems and keys correspond. The lower ends of the key stems are located side by side, in horizontal, transverse alinement, and pivotally connected to the horizontal arms of bell crank levers 16 freely pivoted on a shaft 11. The vertical arms of levers 16 terminate in horizontally alined nose portions 16', each in front of one of ten stop fingers 18. These stop fingers are rigidly mounted on a shaft 19 and arranged within the same parallel, spaced, planes as levers 16, as indicated in Fig. 2. The fingers 18 are also rotatively displaced about their shaft 19 in the order indicated in Fig. 4. Accordingly, each finger 18 must move a different distance counter-clockwise to reach the nose portion 16' within its plane.

The left end of shaft 19 (as viewed in Fig. 2) rigidly carries a pinion 80 meshed with a wide gear drum 81 freely, rotatably carried by a shaft 82. Meshed with the top of drum 81 are nine toothed item indicating wheels 83. Each wheel 83 has ten teeth marked on their faces with indicating numerals 0 to 9 to be viewed through a suitable sight opening in the top of casing 40.

Indicating wheels 83 are freely rotatably mounted on a shaft 85 journaled between frame plates 11, 86, and 87 (see Fig. 2). The wheels 83 lie between the spaced sides of an H-shaped carriage 88 (see also Fig. 1). The sides of the carriage, at their front ends, are forked to slidably receive shaft 85. At their rear, the carriage sides are formed with threaded holes for coaction with the threaded portion of a shaft 89.

Carriage 88 is thus mounted on shafts 85 and 89 for slidable movement along the shafts to be advanced by rotation of shaft 89.

Shaft 89 is rotatably journaled between frame plates 11, 86, and 87. Rotation of shaft 89 through coaction of its threaded portion with the threaded apertures of the carriage effects movement of the carriage along shafts 85 and 89. As the carriage moves along these shafts, it slides wheels 83 along shaft 85.

In the initial, home, positions of the parts, the carriage is at the extreme right of its travel (as viewed in Figs. 1 and 2) and the item wheels 83 are entirely clear of all nine right hand punch slides 10a, t, and c. Each step of movement of the carriage to the left (Fig. 1) will move one of wheels 83 out of mesh with drum 81 and into mesh with rack teeth 47 of the unit order slide 10c. Thus, the first step of movement of the carriage brings the first wheel 83 from the left (Figs. 1 and 2) clear of drum 81 and into mesh with teeth 47 of the right hand or unit order slide 10c. The next step brings this first wheel 83 into mesh with the second or tens order slide 10c, and, at the same time, moves the second wheel 83 into mesh with the units order slide 60.

10c. In this manner, successive steps of travel of the carriage mesh the wheels 83 successively with the slides 10a, t, and c. At the end of nine steps of transverse movement of carriage 88, all nine wheels 83 will have moved off drum 81 and into mesh with the nine slides 10a, t, and c.

The transverse movement of carriage 88 is effected under control of keys 75. Each time a key 75 is depressed to enter a value in a wheel 83, it causes a step of movement of carriage 88. Should the keys be depressed nine times to set up the nine wheels, then all nine wheels will be meshed with all nine slides 10a, t, and c. There is one key operation required for the kind of sale and two key settings for the clerk's number. When the price of the article is the maximum six denominational order figure, six key operations are required to set the price. Thus, the maximum possible settings are nine. However, the price may be less than a six order figure, for example, 8.50 in which case only three wheels 83a will be set in addition to the setting of the one wheel 83t and the two wheels 83c, making a total of six settings, so that the last three wheels will remain on drum 81 and will not be meshed with the slides. The other six, key-set, wheels 83 will be in mesh with the first six slides 10 from the right (Fig. 1). The three left hand slides 10a will not be in mesh with any of wheels 83.

The setting of the slides 10a, t, and c is effected by their advance under control of wheels 83 meshed therewith, in a manner which will be brought out later. Unless provision were made to the contrary, the slides 10a not meshed with wheels 83 would move unimpeded to their "9" positions, resulting in a wrong record of the price being punched and printed. To avoid this error, the slides 10a not in mesh with wheels 83 must be restrained from advancing beyond their "0" positions. For this purpose, the left leg of carriage 88 (as viewed in Figs. 1 and 2) is formed at its front end with a depending laterally extending finger 80 (see also Fig. 13) which lies in front of all nine slides 10a, t, and c when the carriage is in the initial, right hand position.

Finger 80 when in front of a slide blocks advance of the slide beyond its "0" position. When the carriage moves one step to the left to mesh the first wheel 83 with the first slide, then finger 80 moves away from the front of the first slide. As successive steps of travel of the carriage are effected to successively mesh the wheels 83 with the slides 10a, t, and c, the blocking finger is displaced from in front of the successively meshed slides. At the end of nine steps of travel, all nine wheels 83 are meshed with these slides 10, and finger 80 is completely displaced to one side of the slides.

Pinion 88 of shaft 79 and item indicating wheels 83 are both in mesh with gear drum 81, and are of equal diameters so that the pinion and wheels move through equal arcs upon rotation of the drum. Indicating wheels 83 and shaft 79 thus have ten corresponding differential positions. These ten positions of a wheel 83 are defined by its indicating teeth 0, 1, 2 . . . 9 while the corresponding positions of shaft 79 are defined in the same order by stop fingers 78—0, 1, 2 . . . 9.

Referring to Fig. 7, shaft 82, on which drum 81 is rotatably mounted, rigidly carries a pinion 92 (see also Figs. 1 and 2) meshed with a gear 93 rotatably mounted on a shaft 94 carried by the frame plates 86 and 87. Rigid with the side of gear 93 is a pinion 95 meshed with a gear sector 96 which is freely pivoted on a stud 97 car-

ried by frame plate 86. A spring 98 connected to gear 96 urges the gear sector clockwise (Fig. 7). Sector 96 has a travel of about 40° and the ratio of gearing 96, 95, 93, 92, 81, and 83 is such that the full stroke movement of sector 96 is capable of producing eleven revolutions of wheels 83, more than sufficient to move each of the nine indicating wheels 83 through an entire revolution.

Shaft 82 has fixed to it an arm 99 adjacent the side of drum 81. In the initial position of the parts, arm 99 is engaging the free end of a pawl 100 pivoted to the side of drum 81 and urged by a spring 100' towards arm 99 and into limiting engagement with a pin 101 extending from the side of the drum. When shaft 82 is rotated clockwise, its arm 99 coacts with pawl 100 to rotate drum 81 in the same direction. During the counterclockwise, restoring, revolutions of shaft 82, its arm 99 will withdraw from pawl 100 and at each revolution, the arm will ride past the pawl, spring 100' yielding to permit the pawl to be cammed aside. Thus, arm 99 and pawl 100 provide a one-way, clockwise, driving connection between shaft 82 and drum 81. Drum 81 is never moved counterclockwise, as will later be brought out, but is moved only clockwise by the aforesaid one-way driving connection, and under control of pinion 80 with which it is meshed.

Drum 81 cannot move clockwise unless pinion 80 and its shaft 79 are free to rotate counterclockwise (Figs. 4 and 11). Shaft 79 fixedly carries a disk 102 (see Figs. 1, 2, and 11) which has ten teeth 103, one of which is normally in engagement with the nose end 104' of a bell crank lever 104. Teeth 103 are spaced correspondingly to the spacing of stop fingers 78 about shaft 79. When nose end 104' is engaged with a tooth 103, shaft 79 cannot rotate counterclockwise and drum 81 is not free to be rotated clockwise.

Lever 104 is rotatably carried by shaft 77 and is urged counterclockwise by a spring 105 (Figs. 4 and 11) to engage its nose end 104' with a tooth of disk 102. The horizontal arm of lever 104 is bent angularly to provide a transverse lug 106 extending under the left hand arm of a bail 107 pivoted on shaft 77.

The cross bar 107' of the bail underlies the lower edges of the horizontal arms of all ten bell crank levers 106 which are pinned to the ten keys 75 (see Fig. 4). Spring 105 acting through lever 104 and its lug 106 urges bail bar 107' upwardly to maintain contact with the lower edges of the horizontal arms of levers 106 and in so doing, the spring helps to force keys 75 to their upper positions. The keys are additionally urged to upper positions by springs 108 acting on levers 106.

Riveted to the left side of bail 107 is a plate 109 having two sets of reversely inclined ratchet teeth 110. Each set of teeth 110 coacts with one of the end teeth 111 of the full stroke toggle pawl 112. A spring 113 acting on the pawl holds it set in either clockwise or counterclockwise position.

When any of the ten keys 75 is depressed, it rocks the connected lever 106 clockwise (Fig. 4) which depresses common bail 107 and the toothed member 109 carried by the bail. Once depression of a key is begun, the key cannot rise again until the full down stroke has been completed due to restraining coaction between the lower tooth 111 of pawl 112 with the lower set of teeth 110 of member 109. When a full down stroke of the key is made, then upper shoulder 114 of member 109 strikes projection 115 of pawl 112 and rocks the pawl counterclockwise. When

the operator releases pressure on the depressed key, springs 105 and 108 combine to force the key to its upper position and during restoration of the key, upper tooth 111 of pawl 112 engages with the upper set of ratchet teeth 110 of member 109 to prevent depression of the key before it has finished its up stroke. Just before the end of the up stroke of the key and of bail 107, the lower shoulder 114 of member 109 strikes lug 115 of the pawl and causes return of the pawl to initial clockwise position.

At the beginning, all nine item indicating wheels 83 are sitting on top of drum 81, each wheel at zero position, and correspondingly shaft 79 is at zero position with detent 104' engaging a tooth 103 of disk 102 to prevent rotation of the shaft 79, drum 81, and wheels 83 under the influence of spring 98.

When any of the keys is depressed, it actuates the connected lever 76 to place the nose end 76' of the lever in the path of rotation of the stop finger 78 which is in the same plane. Further, when the lever 76 is actuated, it acts on bar 107' to rock bail 107 clockwise (Fig. 4). The bail in turn acts on lug 106 of bell crank lever 104 to rock the lever clockwise, opposed by the pull of spring 105. As a result, detent end 104' of lever 104 is released from the teeth of disk 102. There is nothing now to restrain rotation by spring actuator 98 of shaft 79, its pinion 80, drum 81, wheels 83, gears 92, 93, 95, and 96. Shaft 79 and the other elements of the above gear train, when released by detent 104', rotate under the influence of spring 98 until the nose end 76' of the lever 76 connected to the depressed key is engaged by the associated stop finger 78. On the up stroke of the key, connected lever 76 returns in a counterclockwise direction (Fig. 4), withdrawing its nose end 76' from the stop finger 78 engaged with the nose end and releasing shaft 79 for a supplementary rotation counterclockwise. During the upstroke of the key, spring 105 also restores lever 104 to replace its detent end in the path of rotation of a tooth 103 of disk 102, thus arresting the supplementary movement of shaft 79. The total of the initial and supplementary movements of shaft 79 displaces the shaft through an even multiple of its differential positions. Correspondingly, item wheels 83 will have moved through the same number of their differential positions.

For example, depression of the "0" key releases common detent 104' from shaft 79 and moves "0" lever 76 to place its nose end 76' in the path of the "0" tooth 78. At "0" position of the parts, "0" tooth 78 is below "0" nose end 76' so that shaft 79 makes almost a full revolution before the "0" tooth engages the coacting nose end 76'. Then during rise of the "0" key, the "0" nose end 76' is withdrawn from the "0" tooth 78 and common detent 104' moves between a pair of teeth 103 of disk 102. Shaft 79 now rotates an additional amount until arrested by engagement of a tooth 103 with detent 104'. The total movement of the shaft will be through one complete revolution at the end of which the "0" stop finger 78 will again be in the position from which it started. Correspondingly, item wheels 83 meshed with drum 81 will have moved through one revolution from "0" position to "0" position.

If with the parts in "0" position, the "1" key key is depressed, then "1" lever 76 will be moved forward and common detent 104' released from restraint on shaft 79. Shaft 79 will first rotate until the "1" finger 78 engages "1" nose end 76';

then on the upstroke of the key, the shaft will be released for a further, slight, movement until arrested by detent 104'. Similarly, depression of the other keys will cause movement of the shaft from "0" position through the number of positions indicated by the depressed key. 5

The reason for effecting part of the movement of the shaft upon the down stroke and the remainder of the movement upon the up stroke of the key is to correctly time the release and arrest 10 of shaft 79 by the oppositely moving nose end 76' and detent 104' and to provide clearance between detent 104' and teeth 103 when the detent returns to restraining position.

If the shaft 79 were to move the complete differential distance upon the down stroke of the key, at the end of this movement, a tooth 103 would be exactly in line with detent 104'. Then when the active nose end 76' released the stop finger engaged therewith, shaft 79 might rotate 20 slightly before detent 104' could move above the aligned stop surface of the tooth 103 in front of the detent. As a result, the detent would fail to engage the proper tooth 103 and shaft 79 would move an additional step. Further, if during return of the detent end 104', it were exactly 25 in line with a tooth 103, then it might strike the edge of the tooth and be unable to move above the tooth. By moving shaft 79 through less than its full differential distance upon the down 30 stroke of the key, detent 104' can move with complete clearness above the surface of the tooth 103 below it and the remainder of the differential movement can be conveniently effected to bring the tooth and detent into engagement. 35

When shaft 79 and item wheels 83 on drum 81 have been moved by depression of a key 75 to a differential position other than "0", the following key depression will not cause movement of the shaft and item wheels through the same 40 number of steps as represented by the number on the latter key, but through such a number of steps as will bring the shaft and wheels to the differential position corresponding to the depressed key. For example, if shaft 79 is in "1" 45 position, its "1" stop finger 78 will be at the point initially occupied by the "0" finger. Now, if a "1" key 75 is depressed, shaft 79 will make a full rotation, in the same manner as described above in connection with the "0" setting, and under the successive control of the "1" nose end 76' and the common detent 104' the shaft will again be in "1" position. 50

If the shaft is in "1" position and a "2" key 75 is operated, then the shaft will move one 55 step before it is completely arrested and the "2" finger 78 will be in the position in which the "0" finger 78 is shown in Fig. 4. This latter position may be referred to as the reference position. If shaft 79 has finger 78-8 at the 60 reference position, then depression of the "4" key 75 will cause movement of the shaft through six steps to bring the "4" finger 78 to the reference position. Similarly, no matter in what differential position shaft 79 may be, depression 65 of a key 75 will cause the shaft to move through the number of steps required to bring it to the position represented by the depressed key. Correspondingly, those item wheels 83 still meshed with drum 81 will move from any differential 70 position they occupy to the new position represented by the key last depressed. For example, if a wheel 83 on drum 81 reads "4" and the "6" key 75 is depressed, this wheel 83 will move two differential steps to read "6". 75

As explained above depression of a key differentially sets all the wheels 83 meshing with drum 81 to the common position represented by the key. Thus, initially, all nine wheels are on the drum and operation of key 75—8, for example, will set the nine wheels similarly, each to a "6" position.

In addition to setting wheels 83, operation of any of keys 75 controls an escapement mechanism 10 to effect rotation of screw shaft 89 to an extent such as to move carriage 88 and wheels 83 one step to the left, as viewed in Figs. 1 and 2, thereby removing one wheel 83 from drum 81 and meshing this wheel with the right hand end slide 10c.

15 Referring particularly to Figs. 1 and 10, the escapement-controlled means for rotating screw shaft 89 comprises gear sector 120 pivoted on stud 121 carried by frame plate 81. A spring 122 connected to sector 120 urges it clockwise (Fig. 10) to rotate gear train 123, 124, 125 and 126. Gear 126 meshes with a pinion 127 fixed to screw shaft 89. Also meshed with gear 126 is a pinion 128 (Figs. 1, 2, and 10) freely, rotatably, carried by shaft 79. Rigid with pinion 128 are two teeth 129 and 130 spaced apart along shaft 79 and having their radial, stop surfaces 20 extending along the same diametral line and 180° apart.

Stop tooth 129 is normally in engagement with 25 the nose end of a detent arm 131 rotatably carried by the left end of shaft 77 (see Fig. 1). Adjacent arm 131, shaft 77 has rigidly fastened to it another detent arm 132 located in the plane of tooth 130. The nose end of arm 132 is initially in front of, slightly below, and remote from stop tooth 130. A lug 133 on arm 132 is held engaged with a stud 134 on arm 131 by a spring 135 connected to the stud 134 and to the frame.

Referring to Fig. 4, when a key 75 is depressed 40 to set wheels 83, it rocks the connected lever 76 which in turn rocks common ball 107 clockwise. Underlying the left side of ball 107 (as viewed in Fig. 2) is the transversely bent lug 138' formed at the free end of an arm 138 pinned to shaft 77. Thus, when ball 107 rocks clockwise due to depression of a key, arm 138 and its shaft 77 are rocked similarly. Since detent arm 132 is pinned to shaft 77, it will also be moved clockwise (Fig. 10) to a position directly 45 underlying stop tooth 130 and in the path of counterclockwise rotation of the latter tooth. At the same time, as arm 132 moves to the right, its lug 133 acts on stud 134 of arm 131 to move the latter, against the pull of spring 135, in the same direction, thereby displacing the nose end of arm 131 from engagement with stop tooth 129.

The gear train comprising elements 120, 123, 124, 125, 126, 127 and 128 is now free to be rotated by the power of spring 122. Pinion 128 50 rotates a slight distance anticlockwise bringing its tooth 129 above and clear of the nose end of detent arm 131 and its tooth 130 into engagement with the top of detent arm 132. During this rotation of pinion 128, gear 126 rotates pinion 127 and its shaft 89 through a small angle, causing movement of the item wheels 83 on drum 81 slightly to the left (Figs. 1 and 2), but not to such an extent as to demesh the left hand one of the latter wheels from the drum.

55 The above, initial, escape action of the wheels 83 is the result of depression of a key 75. As previously explained, the depression of a key 75 also causes an initial setting operation to partially set the wheels 83 on the drum to the reading represented by the depressed key. During

the up stroke of a key, wheels 83 are given the final portion of the setting operation to complete their setting to the differential position selected by the key. Also, during the upward, return, stroke of the key, the escapement means 60 operates to effect a supplementary rotation of shaft 89 to complete the lateral step of movement of carriage 88 and wheels 83. The completion of the setting of wheels 83 overlaps the early portion of the supplementary escape movement of carriage 88 and takes place before the left hand wheel 83 meshed with drum 81 has left the drum. In brief, the relation of the parts and their timing are such that upon the down stroke of a key, all but a minor portion of the 15 setting movement of the item wheels is carried out while only a slight portion of the escape step is effected, and upon the up stroke of the key, the slight, fractional, remainder of the wheel setting is completed and the major portion of the escape step takes place.

During the rise of the key, bail 107 moves counterclockwise (Fig. 4), permitting spring 135 to rock detent arm 131 to the left to position the nose end of the arm in the path of counterclockwise movement of associated stop tooth 129 which at this time is above the nose of arm 131 due to the initial escape movement. When arm 131 is rocked to the left (Fig. 10) by spring 135, through coaction of stud 134 and lug 133, arm 30 132 is similarly moved to the left, thereby withdrawing its nose end from engagement with tooth 130. This leaves pinion 128 free to rotate counterclockwise under the influence of spring 122 until tooth 129 engages the nose of arm 131. 35 The parts of the escape means are then in initial position, shown in Fig. 10 and pinion 128 has completed a revolution. As a result of the supplementary, final, escape movement, gear 126 has rotated screw shaft 89 to complete the lateral step of movement of carriage 88, and to thereby entirely remove from drum 81, the left hand one of the group of wheels 83 meshed with the drum at the beginning of the last key operation.

In above manner, each time a key is operated, it causes all those wheels 83 which are still meshed with drum 81 to be differentially and commonly set to the position represented by the key and also causes escapement mechanism to shift the wheels laterally to move the left hand one of those wheels off the drum and onto the first units order, slide 10c. In nine key operations, wheels 83 will be successively displaced to the left until they are all removed from 81 and in mesh with the nine slides 10a, t, and c. Similarly, one to eight key operations will move the same number of wheels 83 off drum 81 and onto the same number of slides 10. 50

The reason for effecting the escapement movement in two parts and under control of two detents is because the length of time during which the operator holds a key depressed is indeterminate. If only one detent and escapement tooth were provided, there would be no assurance that the detent after release by the depression of the key would be restored in time to arrest the tooth when it had made one revolution. By utilizing the two detents 131 and 132, at least one is always in position to engage the coacting tooth 129 or 55 130 and regardless of the length of time during which a key is held down, the escapement mechanism will move only one full step for each reciprocation of a key.

As an example of the setting and escape opera- 75

tions, assume the price of an article is 8.50, the kind of sale is "charge send" represented by code number 4, and that the clerk's number is 11. Initially shaft 79 is in "0" position and the nine wheels 83 are on drum 81. The operator first 5 depresses key 75-8, causing release of detent end 104' of lever 104 from disk 102. Shaft 79 moves almost eight differential steps from its "0" position until arrested by engagement of stop finger 10 78-8 with the nose end of the vertical arm of lever 76-8, and drum 81 and the nine wheels 83 move synchronously with shaft 79. Depression of key 75-8 also caused release of detent 131 from tooth 129 of pinion 128, and simultaneously 15 caused movement of detent 132 into the path of movement of tooth 130 of the pinion. Spring 122 acts, upon release of pinion 128, to rotate the latter a slight amount until tooth 130 engages detent 132. This initial rotation of pinion 128 is 20 accompanied by corresponding rotational movements of gear 126 and pinion 127. Shaft 89 of the latter pinion coacts with carriage 88 to shift the latter and the nine wheels 83 slightly to the left.

When the operator releases key 75-8, lever 25 76-8 rocks counterclockwise (Fig. 4), withdrawing its nose end from stop finger 78-8; simultaneously spring 105 moves detent end 104' above a tooth 103 of disk 102. Shaft 79 rotates a slight amount, completing its eight step movement from 30 "0" position, and is then arrested by engagement of the detent and 104' with the tooth 103. During the latter rotation of shaft 79, the nine wheels 83 on drum 81 are correspondingly rotated and now set to read "8".

35 During rise of key 75-8, detent 132 is displaced from tooth 130 of pinion 128, and detent 131 is interposed in the path of rotation of tooth 129 of this pinion. Spring 122 acts now to rotate pinion 128 through the greater part of a revolution until tooth 129 engages detent 131, and the pinion is thus arrested in initial position. During 40 the latter rotation of pinion 128, gear 126 rotates pinion 127 and its shaft 89 to shift carriage 88 and wheels 83 to the left for the major part of 45 their escapement step. The differential setting of wheels 83 to their "8" positions is completed during the first part of this latter escape step, and then as the escapement continues, the first wheel 23 from the left (Figs. 1 and 2) moves off drum 50 81 and onto unit slide 10c. At the end of the escapement step, this first wheel 83 reads "8". The other eight wheels are still on the drum.

The clerk now depresses key 75-5; shaft 79 rotates from its "8" setting an amount just short 55 of seven steps before being arrested by engagement of stop finger 78-5 with lever 76-5. Upon the up stroke of the key, shaft 79 covers the remaining distance to its "5" position where it is arrested by detent 104'.

60 The eight wheels which at the beginning of the operation of key 75-5 were on drum 81 are set now at "5". The reciprocation of the key effected escape of the carriage 88, bringing the left hand one of the latter eight wheels off drum 81 and 65 onto unit slide 10c. The left hand one of all nine wheels 83 had been set during the first key operation to "8" and demeshed from drum 81, so that it was not affected by the rotation of drum 81 which took place upon the second key operation and remains at "8". The second escape operation of carriage 88 moves the latter wheel 83 onto the tens order slide 10c which is the second one from the right (as viewed in Fig. 1).

In the same manner, keys 75 are successively 70 depressed to set up 0, 4, and 11 on wheels 83.

At the end of the six required key operations, the first wheel from the left will read 8, and be in mesh with units dollar order slide 10a, the next wheel will read 5 and mesh with dimes order slide 10a, the third wheel will read 0 and mesh with 5 cents slide 10a, the fourth wheel will stand at 4 and mesh with transaction slide 10t, and the fifth and sixth wheels will each read 1 and be in mesh with tens and units slides 10c. Through a suitable sight window, the reading 850 will appear under a suitable heading (not shown) denoting "amount," "4" will appear under a heading (not shown) denoting "kind of sale," and "11" will appear below a heading (not shown) indicating "clerk."

The last three wheels 83 will remain on drum 81, each wheel reading "1" as a result of the last key setting. Also, the last three higher order slides 10a, namely, the thousands, hundreds, and tens of dollar orders slides will be out of mesh 20 with any of wheels 83. The abutment 90 provided on carriage 88 will be in front of these last three slides 10a, as has been explained before.

During the cycle of shaft 39, which is initiated by the operator subsequent to the setting operations, the item wheels 83 remaining on drum 81 are set to "0". For this purpose, a gear 136 at the right end of cam shaft 39 (as viewed in Figs. 1 and 3) carries at one side a cam piece 137 (see also Fig. 9). During the initial portion of revolution of shaft 39, cam piece 137 rides past the free end of an arm 139' fixed to one end of a shaft 139, and thereby rocks shaft 139 clockwise (Fig. 9). The opposite end of shaft 139 has fast to it an upright arm 140 connected by a link 141 to an arm 142 loosely mounted on shaft 77 (see Figs. 4 and 11). Arm 142 is in the same vertical plane as a special zero stop finger 78'-0 secured to shaft 79 at the left of the ten-key controlled fingers 78 and disposed in the same relation to 40 arm 142 as that of the key-controlled "0" finger 78 to nose end 76' of "0" lever 76. Arm 142 has a lug 143 held engaged with pin 144 on detent arm 104 by spring 105.

When cam lug 137 rocks shaft 139 clockwise, 45 the shaft, through arm 140 and link 141, rocks arm 142 in the same direction. Arm 142, through coaction of lug 143 and stud 144, displaces detent 104' from the teeth 103 of disk 102, permitting spring 98 (Fig. 7) to rotate gear drum 81 and the item wheels 83 thereon until special "0" finger 78'-0 abuts the nose end of arm 142.

Cam piece 137 holds arm 139' depressed long enough for shaft 79 to make substantially one revolution. When the cam lug rides off the end 55 of arm 139, then spring 105 restores detent arm 104 which in turn restores arm 142. Arm 142 thereupon releases finger 78' and shaft 79 completes its movement to "0" position, where it is stopped by detent 104' engaging a tooth 103 of 60 disk 102. Shaft 79, drum 81, and the item wheels 83 on the drum are now at "0" positions.

Subsequent to the above described setting of the wheels on drum 81 to "0", the spring actuator 98 of drum 81 is retensioned. This is done by a cam 145 (see Figs. 1, 3, and 7) fast to cam shaft 39. During the revolution of shaft 39, cam 145 acts on roller 146 of gear sector 96 to rock the sector counterclockwise, thereby retensioning spring 98. As sector 96 moves counterclockwise 70 through gears 93 and 94, it rotates pinion 92 and its shaft 82 in the same direction. During the counterclockwise revolutions of shaft 82, arm 99 on the shaft rides over pawl 100 without restraint due to yielding of spring 100. Any tendency of 75

drum 81 to rotate counterclockwise during such movement of shaft 82 is effectively prevented for the following reasons:

- Counterclockwise motion of drum 81 would 5
 5 rotate shaft 79 clockwise (Fig. 7) and the latter movement would be effectively stopped by engagement of the top of detent end 104' with the tooth 103 directly above it (see Fig. 11) before shaft 79 could move one differential step. Further, if any item wheels 83 are still on drum 81, they are at zero positions and would also prevent 10 tendency of the drum to rotate counterclockwise. This is because each wheel 83 has a home or zero position dog 148 (see Fig. 6a) which when the 15 wheel is in zero position, is engaged with a flat shoulder 149 formed along shaft 85 of the wheels (see also Fig. 1).

For drum 81 to rotate counterclockwise requires clockwise movement of the wheels 83 on 20 the drum, which are now at "0" position and cannot move clockwise because of dogs 148 abutting shoulder 149 of shaft 85. As a result, drum 81 cannot move counterclockwise. Nor can the drum move clockwise, unless released by disengagement 25 of detent 104' from teeth 103 of disk 102, which occurs only under control of keys 75 or cam 137.

Drum 81 has three times as many teeth as an item wheel 83 and when the latter is in "0" position, pawl 100 on the drum may be in either of 30 three "0" positions, the one shown in Fig. 7, and two others successively located one-third of a revolution apart. When restoring cam 145 leaves roller 146, arm 99 is in the position shown in Fig. 7. If pawl 100 is also in this position, then 35 the pawl prevents clockwise rotation of arm 99. If pawl 100 is in either of the two successive positions further on in a clockwise direction, then spring 98 moves arm 99 clockwise 120° or 240° until it engages pawl 100. The parts 100 and 99 40 are now in required relation for effecting clockwise rotation of drum 81 during the next series of key-setting operations. The maximum possible number of rotations of item wheels 83 to be imparted by drum 81 is nine. The ratio of gearing 45 and the extent of movement of sector 96 are such as to be capable of rotating drum 81 through three and two thirds revolutions, providing therefore a surplus of two-thirds revolutions. Accordingly, even if after restoration of 50 arm 99, it has moved ahead under the force of spring 98 through two-thirds of a revolution, its remaining capacity for effecting three more revolutions of drum 81 is sufficient to furnish the maximum of nine revolutions of the nine item 55 wheels 83.

Those item wheels 83 which have moved off drum 81 and into mesh with punch slides 10a, t, and c control the setting of the slides to positions corresponding to the settings of the item 60 wheels. This is done as follows: Referring to Fig. 6, slides 10a, t, and c are connected to arms 60 pivoted on a rod 61 and urged by individual springs 62 towards the left to move the connected slides in the same direction. This movement is normally prevented by cross bar 63 engaging the front of arms 60. Bar 63 is fastened to arms 64 and 64' (also see Fig. 3) pivoted on rod 61. Arm 64' is pivotally connected to one end of a bar 65, forked at the other end to slidably 65 embrace shaft 39. On bar 65 is a roller 65' engaged with a cam 66 on cam shaft 39. When the cross bar is permitted by cam 66 to move to the left, then springs 62 act on arms 60 to move them in the same direction. The arms in turn 70 move slides 10a, 10t, and 10c towards the left 75

and through coaction of teeth 47 on these slides with the teeth of wheels 83 meshed with the slides, the wheels are rotated clockwise. The extent of this rotation is determined by engagement of the zero position dogs 148 of the wheels with shoulder 149 of shaft 85 (see Fig. 6a). Slides 10a, t, and c thus move differential distances to the left until arrested by the zeroizing of the item wheels 83 meshed with the slides; and as a result, their punch pins 12 are positioned to 10 perforate card T according to the items set up by keys 75. Any of slides 10a which have not been meshed with wheels 83 by the key operations, as when the amount 8.50 is set up, are arrested before they move out of their "0" positions by the carriage abutment 90 which is located in front of these slides.

Also meshed with teeth 47 of slides 10a, t, and c are pinions 150 carried by the right hand ends of nested shafts 151 (as viewed in Figs. 1 and 12), the opposite ends of which carry type wheels 43a, t, and c. Thus, when slides 10a, t, and c advance to differential positions under control of wheels 83, the slides rotate pinions 150 to set type wheels 43a, t, and c to print the items set up by keys 75.

Those higher order slides 10a (at the left in Fig. 1) which have not been set under control of wheels 83 but have been retained in "0" positions by abutment 90 do not rotate their pinions 150 and therefore the corresponding higher order type wheels 43a also remain in zero positions. The highest order wheel 43a has no "0" type lug since it is not necessary to print "0" in the highest order of the amount while the remaining wheels 43a have "0" type to print "0" in an intermediate order of the amount item.

Subsequent to the setting of slides 10a, t, and c to differential positions, alining bar 36 moves into notches 37 of the slides to exactly aline the slides, and the type wheels geared thereto, in their various differential positions. Alining bar 36 is carried between the sides of a bail 34 freely pivoted on a rod 35 mounted between frame plates 17 and 18 (see Figs. 1, 5, and 6). The sides of the bail have pin and slot connections to arms 32' and 32a fast to a shaft 33. Arm 32a is part of a three-armed lever, arms 32b and 32c of which coact respectively with cams 38 and 38' of shaft 39. Cam 38, during the revolution of shaft 39, rocks lever 32a—b—c, its shaft 33, and arm 32' thereof clockwise (Fig. 5) to effect downward movement of bail 34 and alining bar 36. This takes place after the slides 10a, t, and c 55 have been set under control of item indicating wheels 83. Cam 38' coacts with arms 32c to restore the bail and alining bar 36 after the punching operation.

When slides 10a, t, and c have been set under 60 control of wheels 83, the latter are at zero positions, and may be returned to drum 81. To restore these wheels to the drum, carriage 88 must be moved to the right (Fig. 1) by rotation of threaded shaft 89 in a clockwise direction (Fig. 65 10). This is done by a cam 158 on shaft 39 (see Figs. 1, 3, and 10). During the cycle of shaft 39, cam 158 engages follower roller 159 on gear sector 120 to rock the latter counterclockwise (Fig. 10). In so doing, spring 122 of the 70 escapement mechanism is retensioned. As gear sector 120 moves counterclockwise, it causes clockwise movement of pinions 127 and 128. Clockwise rotation of pinion 128 is not prevented by detent arm 131, since escapement tooth 129 75

merely cams the nose on this arm outwardly, as permitted by yielding of spring 135.

Clockwise rotation of pinion 127 moves its shaft 89 in the same direction. This rotation of shaft 89, through coaction of its threaded portion with carriage 88, moves the carriage and all nine wheels 83 mounted between the sides of the carriage towards the right (Fig. 1). At the end of this movement, the nine wheels 83 are entirely demeshed from slides 10a, t, and c and again meshed with drum 81 in their initial positions.

During return of the wheels 83 to drum 81, it is desirable to relieve the pressure between shoulder 149 of shaft 85 and the dogs 148 of the wheels. Further, the teeth of the wheels may not be in perfect alignment with the teeth of drum 81 and if dogs 148 were firmly engaged with shoulder 149 of shaft 85, the wheels would be unable to rotate slightly so as to bring their teeth into line with the teeth of drum 81 and as a result, the wheels would be unable to return to the drum. The left ends of the teeth of drum 81 are rounded to facilitate meshing of wheels 83 therewith when the wheels slide back onto the drum. If the wheels are free to rotate, then if their teeth are not exactly aligned with the drum teeth, the rounded ends of the latter teeth cam against the teeth of wheels 83 to rotate the wheels slightly until their teeth are in alignment. To permit this aligning rotation of wheels 83 and to relieve the pressure between dogs 148 and shoulder 149, shaft 85 is rocked clockwise (Fig. 4) under control of a cam 160 (Figs. 1, 3 and 4) on shaft 39. The cam is engaged by a roller 161 at the right end of a link 162 slidably guided at said end by shaft 39 and connected at the opposite end to a crank arm 163 depending from shaft 85.

The high dwell portion of cam 160 rides off roller 161 after slides 10 have been locked in place by aligning bar 36. A spring 164 thereupon moves link 162 to the left (Fig. 4), rocking arm 163 and shaft 85 clockwise. As a result, shoulder 149 of shaft 85 is moved away from zero pawls 148 of wheels 83 (see Fig. 6a), thereby preventing binding between the wheels 83, shaft 85, and drum 81 while the wheels are being returned into mesh with the drum. At the beginning of the next cycle of shaft 39, cam 160 positively restores shaft 85 and shoulder 149 to their normal mal positions.

As shown in Figs. 3 and 9, gear 136 of shaft 39 is meshed with a gear 250 operated by a crank handle 251. Two turns of the handle are effected by the operator to effect a one-revolution cycle of shaft 39. Rotation of shaft 39 is permitted only counterclockwise (Fig. 9), reverse rotation being prevented by a pawl 252, of spring metal, engaging gear 136. Normally, shaft 39 is locked against operation until a card T is inserted in punching position, indicated in Fig. 1. When the card is thus inserted, its leading ledge engages a plate 233 (Figs. 3 and 8) and rocks the latter rearwardly against resistance of a spring 234. Yieldably held to plate 233 by a spring 244 and movable with the plate 233 is a second plate 241. The rearward movement of plate 233, therefore, effects corresponding movement of plate 241, withdrawing a block 246 on the latter plate from in front of edge 247 of a cam 248 fast to shaft 39. The latter may now be rotated by operation of handle 251. After the punching operation, edge 247 of cam 248 rocks a lever 239 downwardly against resistance of spring 240. Lever 239 is pivotally connected to plates 233 and 241, and upon depression of the

lever, the plates are moved downwardly to remove the upper part of plate 241 from the path of ejection of card T. The card is then ejected into delivery magazine 223.

With ejection of the card, spring 234 returns plates 233 and 241 to initial forward positions, and block 246 of plate 241 is again in position to abut edge 247 of cam 248 to stop shaft 39 at the end of its revolution.

While there has been shown, described, and pointed out the fundamental features of the invention as applied to a single modification, it will be understood that various omissions, substitutions, and changes in the form, details, or operation of the device illustrated may be made by those skilled in the art without departing from the spirit of the invention. It is the intention, therefore, to be limited only as indicated by the scope of the following claims.

What is claimed is:

1. In combination; a group of toothed item wheels, each independently movable and each having differential positions corresponding to different values, a wide actuating toothed drum meshed with the group of wheels, means for actuating the drum, a series of value keys, and control connections between said keys and said drum effective upon operation of a key for causing the actuating means to actuate the drum differentially to move the entire group of wheels to a common differential position corresponding to the value selected by the operated key, escapement mechanism operating upon each operation of a key for moving one of said wheels out of coaction with said drums while the remaining wheels stay on the drum and retain their common differential position, said control connections being effective upon the next operation of a key to cause the actuating means to actuate said drum to move said remaining wheels from their last common differential position to a new common differential position corresponding to the value selected by the latter key.

2. In combination; a differentially rotatable wheel having differential positions corresponding to different digital values, a shaft on which the wheel is rotatably mounted, a shoulder on the shaft, a zero element on the wheel engaging said shoulder when the wheel is in zero position, actuating means for the wheel including a device coacting with the wheel for differentially rotating it, value keys, control connections between the keys and the device for causing the latter upon operation of a key to differentially move the wheel in accordance with the value selected by the operated key, escapement mechanism for moving the wheel out of coaction with said device after the wheel has been differentially set by the device, value manifesting means, means for transmitting the value represented by the set position of the wheel to said value manifesting means by rotating the wheel until its zero element engages the aforesaid shoulder, means effective after the transmission of said value for causing said escapement mechanism to restore said wheel to coaction with said device, and means operable prior to the latter action of the escapement mechanism for separating said shoulder and said zero element of the wheel from each other to relieve the pressure of the shoulder on said element during the subsequent restoration of the wheel into coaction with said device.
